DESIGN FOR A FINGER RING OR SIMILAR ARTICLE

Joseph Fleischer, New York, N. Y.

Application May 1, 1946, Serial No. 129,183

Term of patent 3½ years

(Cl. D45—10)

To all whom it may concern:

Be it known that I, Joseph Fleischer, a citizen of the United States, residing at New York city, in the county of Bronx and State of New York, have invented a new, original, and ornamental Design for a Finger Ring or Similar Article, of which the following is a specification, reference being had to the accompanying drawing, forming part thereof.

In the drawing:

Fig. 1 is a perspective view of a finger ring showing my new design;

Fig. 2 is a perspective view of the opposite side of the finger ring shown in Fig. 1; and

Fig. 3 is a fragmentary longitudinal cross-

section of the ring taken through one of the depressed areas.

I claim:

The ornamental design for a finger ring or similar article, as shown.

JOSEPH FLEISCHER.
